ELECTRIC BACON COOKING GRIDDLE

Carmen I. Ward, 3240 Dexter St., Denver, Colo.

Filed Apr. 24, 1961, Ser. No. 64,868

Term of patent 14 years

(Cl. D80—10)

FIG. 1.

FIG. 2.

FIG. 3.

FIG. 1 is a front perspective view of an electric bacon cooking griddle showing my new design; the cover being raised and the drawer partially opened.

FIG. 2 is a rear perspective view thereof in closed position; and,

FIG. 3 is a bottom plan view thereof.

I claim:

The ornamental design for an electric bacon cooking griddle, substantially as shown.
